UNITED STATES PATENT OFFICE.

CHARLES E. JONES, OF CHICAGO, ILLINOIS, ASSIGNOR TO METAL ARTS AND CRAFTS CO., OF CHICAGO, ILLINOIS, A CORPORATION OF ILLINOIS.

DESIGN FOR A DOUBLE-HOOK CLAMP.

45,881.

Specification for Design.

Patented June 2, 1914.

Application filed March 28, 1914. Serial No. 828,091. Term of patent 3½ years.

To all whom it may concern:

Be it known that I, CHARLES E. JONES, a citizen of the United States, residing at Chicago, in the county of Cook and State of Illinois, have invented a new, original, and ornamental Design for a Double-Hook Clamp, of which the following is a specification, reference being had to the accompanying drawing, forming a part thereof.

Figure 1 is a side elevation of my im-

proved design. Fig. 2 is a front elevation of the same.

I claim:

The ornamental design for a double hook clamp as shown.

CHARLES E. JONES.

Witnesses:

C. M. BAUMEISTER,
V. C. LINDSTROM.
